UNITED STATES PATENT OFFICE.

EDWARD JULIUS LONN, OF LAPORTE, INDIANA, ASSIGNOR TO GREAT WESTERN
MANUFACTURING CO., OF LAPORTE, INDIANA, A CORPORATION OF ILLINOIS.

DESIGN FOR A BICYCLE-FRAME.

45,170.

Specification for Design.

Patented Jan. 20, 1914.

Application filed July 16, 1912. Serial No. 709,829. Term of patent 14 years.

To all whom it may concern:

Be it known that I, EDWARD JULIUS LONN, a citizen of the United States, residing at Laporte, in the county of Laporte and State of Indiana, have invented a new, original, and ornamental Design for Bicycle-Frames, of which the following is a specification, reference being had to the accompanying drawing, forming part hereof.

The figure is a view in side elevation of a bicycle-frame, showing my new design.

I claim:

The ornamental design for a bicycle-frame, as shown.

EDWARD JULIUS LONN.
